UNITED STATES PATENT OFFICE.

SOLOMON J. CLUTE AND DANIEL M. DURFEE, OF ROCKWOOD, NEW YORK.

IMPROVEMENT IN GLOVES.

Specification forming part of Letters Patent No. 129,934, dated July 30, 1872.

Specification describing a new and useful Improvement in Gloves, invented by SOLOMON J. CLUTE and DANIEL M. DURFEE, of Rockwood, in the county of Fulton and State of New York.

In the accompanying drawing, Figures 1, 2, 3, and 4 are diagrams showing the several pieces used for the hand and finger coverings of the glove. Fig. 5 is a top view of the glove, and Fig. 6 a section through one of the fingers.

Similar letters of reference indicate corresponding parts.

The gloves upon which ours is an improvement are mainly formed of a palm-piece and two fourchettes, the former being cut so as to lap and constitute the back of the first and fourth fingers, and the latter to form the back of the second and third fingers. With such a pattern of glove it is frequently impossible to cut but the one palm-piece and the two fourchettes from a single skin, owing to various well-known defects existing to a greater or less extent in skins used by glovemakers. Hence there must result a great or corresponding waste of stock and loss of profit to the manufacturer, with proportional increase in cost of the glove to the purchaser. To avoid this is mainly the object of our invention, which we will now proceed to describe.

A in the drawing represents the palm-piece of a glove, which has the finger projections *a b* and *e e'*. The fourchettes, which, in conjunction with the part *e'* of the palm-piece, form the back of the glove and part of the side

portion of the fingers, are marked B C D, and the outline and arrangement of each in the completed glove are fully shown in Figs. 2 to 5, inclusive, so that particular verbal description thereof is unnecessary.

By this method of cutting out gloves the palm-piece is made of such form and size, and so much of the glove is taken up by the three fourchettes, that a skin which is defective in many parts or places may be utilized, where it could not be under the old practice or by use of the ordinary patterns, it being always difficult to cut palm-pieces in sufficient number to use up the skins. This economic result is attained without any material offset by increased cost on account of the slight difference in labor in sewing or making up the glove, labor being always a small item of expense as compared with the stock or material used. Thus the manufacturer is enabled to furnish for a less price a glove fully equal to the ordinary variety in respect to appearance and durability.

What we claim is—

A glove formed of a palm-piece, A, provided with the finger projections *a b d e e'* and the three fourchettes B C D, arranged as and having the form shown and described.

SOLOMON J. CLUTE.
DANIEL M. DURFEE.
